UNITED STATES PATENT OFFICE.

ROY H. ANDERSON, OF ALLENTOWN, PENNSYLVANIA, ASSIGNOR OF ONE-HALF TO
H. GIBSON HASTINGS, OF ALLENTOWN, PENNSYLVANIA, AND A. HARLAN ELLIOTT,
OF PHILADELPHIA, PENNSYLVANIA.

TOE PROTECTOR.

Application filed June 24, 1924. Serial No. 722,050.

To all whom it may concern:

Be it known that I, ROY H. ANDERSON, a citizen of the United States, and resident of Allentown, in the county of Lehigh and 5 State of Pennsylvania, have invented certain new and useful Improvements in Toe Protectors, of which the following is a specification.

My invention relates to toe protectors for 10 shoe soles and has particular reference to improvements in toe protectors of the kind illustrated, described, and claimed in my prior Patents 1,403,474 and 1,420,302.

In my aforesaid prior patents I disclosed 15 a toe protector consisting of a metallic member including a base portion adapted to underlie the sole of a shoe, a vertical side portion adapted to embrace the edge of the sole, and an inwardly directed flange at the upper edge of the side portion adapted to overlie the top face of the sole. In my prior 20 Patent 1,420,302 I also disclosed means whereby the protector might be adjusted to fit toe portions of shoe soles of different 25 sizes, said means consisting of a slit formed in the base portion of the protector tapering from the rear of the base portion towards its front, so that the side portions might be spread apart to fit the protector 30 to a wide sole, or moved together to fit the protector to a narrow sole. I have found, however, that the provision of adjusting means of this kind weakens the protector, detracts from its appearance and otherwise 35 is disadvantageous, except when the protector is adjusted to its narrowest proportions with the side walls formed by the recess in the base portion abutting one another to lend strength to the device, as 40 otherwise the corner portions of the base adjacent to the recess are liable to become bent away from the sole and mar floors, become caught in carpets, rugs etc. and cause general discomfort to the wearer. It therefore 45 is my present purpose to provide means of an improved nature that, without detracting from the appearance of or appreciably weakening the protector, will permit adjustments to be made therein and will 50 overcome all disadvantages heretofore experienced as a result of the corner portions of the base becoming bent outwardly adjacent to the recess therein.

Additional improvements incorporated in

my present protector consist in forming the 55 base portion with a convex curve both longitudinally and transversely whereby all portions of the protector conform to and fit most perfectly over soles that are curved in similar fashion, and in the provision of 60 an insert plate for quickly and efficiently building up excessively worn toe portions of soles.

With the foregoing and other purposes in view my invention consists in the novel features of construction and arrangement as will be hereinafter more fully described, illustrated in the accompanying drawings and defined in the appended claims.

In the drawings, wherein like characters 70 of reference denote corresponding parts in the different views

Figure 1 is a perspective of the toe portion of a shoe showing my improved protector applied;

Figure 2, an enlarged plan view of the protector looking toward its inner side;

Figure 3, a view similar to Figure 2 showing the protector after an adjustment has 80 been made therein;

Figure 4, a view similar to Figures 2 and 3 showing another adjustment of the protector;

Figure 5, an enlarged detail section on the line 5—5 of Figure 2;

Figure 6, an edge view of the protector looking towards the front thereof; and

Figure 7, a central longitudinal section through the protector.

Referring now to the drawing in detail, 90 10 designates generally a shoe and 11 the sole thereof, with the toe portion of which my improved protector A is adapted for association.

Protector A consists of a metallic member 95 including a base portion 12 corresponding in shape and substantially corresponding in size to the toe portion of the sole to which it is to be applied, said base portion preferably being thicker at its front than at its rear thin edge as and for the purpose set forth in my prior patents aforementioned, although it is not necessarily of this construction since the entire protector may be stamped from metal of uniform thickness 100 105 as will hereinafter become manifest.

Rising from the base portion 12 is a vertical side portion 13 of a height correspond-

ing to the thickness of the sole, the edge of the toe portion of which it is adapted to embrace and extending inwardly from the top of said side portion is a flange 14 of any suitable width for engagement with the upper face of the sole to assist nails or screws that are passed through openings in the base portion into the sole in securing the protector thereon.

10 As is understood my protectors are formed in different sizes to fit different standard sizes of shoe soles, but it happens that adjustments of the protectors are necessary quite frequently to fit them properly with 15 soles of odd sizes, and in order to provide an arrangement that will not detract from the appearance of the protector or appreciably weaken same, and to eliminate as far as possible the liability of corner portions of 20 the base thereof becoming bent outwardly into position where they might become engaged with carpets, mar floors etc. and cause discomfort generally to the wearer, I slot the base portion as at 15 from a point near 25 the front thereof to a point inwardly of, but near the rear thereof, and on the inner face of the base I form kerfs 16 that extend from the rear edge of the base to the adjacent end of the slot 15 whereby weakened lines are 30 formed along which the base portion is adapted to be divided to permit the side portions of the protector to be moved towards one another with the result that the protector is slightly reduced in size.

35 As will be noted from Figure 2 of the drawings the slot 15 diverges towards the rear of the protector as do the kerfs 16 with respect to one another, the side walls of the slot and the kerfs all radiating from a central point near the front of the protector. The kerfs are formed in pairs with one of each pair on opposite sides of a medial longitudinal line through the center of the base, so that by removing the metal between the 40 innermost pair of kerfs a predetermined amount of inward adjustment of the vertical side portions with respect to one another is permitted, such adjustment being limited of course by the walls of the recess formed 45 by the removed metal coming into contact with one another as shown in Fig. 3 of the drawings. If a greater amount of inward adjustment is desired, the metal between the next pair of kerfs is removed and so on, it 50 being understood that as many pairs of kerfs as desired may be provided, although only two pairs are shown in the present instance.

By providing an adjusting means as mentioned, I assure that the abutment of the 60 walls of the recess in the base portion at the rear of the latter regardless of what the amount of the adjustment might be which abutment lends strength to the otherwise separated portions of the base and to a considerable extent overcomes the liability of the corner portions of the base adjacent to the recess becoming bent outwardly as is manifest. Furthermore, the outer face of the base portion always presents an uninterrupted surface except for the slot 15 which of course enhances the appearance of the device over similar devices where the slot 15 extends entirely to and through the rear defining edge of the base portion.

70 As best shown in Figures 6 and 7, I convexly curve the base portion both longitudinally and transversely, so that it will conform to the usual curvature of a shoe sole and so that it will rock or roll on the surface 80 over which a person may be walking whereby all disagreeable clicking noises heretofore experienced with protectors having a flat or substantially flat under face are eliminated.

75 I claim:—

1. A toe protector for shoe soles consisting of a metallic member having a base portion adapted to underlie the sole, said base portion having a slot formed therein extending from a point near the front of the base to a point inwardly of the rear edge of the base thereby to provide a web portion between the rear edge of the base and the adjacent end of said slot adapted to be cut 90 away to permit the sides of the protector to be moved together for purposes of adjusting the protector to sizes smaller than its original side.

2. A toe protector for shoe soles consisting 100 of a metallic member having a base portion adapted to underlie the sole, said base portion having a slot formed therein extending from a point near the front of the base to a point inwardly of the rear edge of the base 105 thereby to provide a web portion between the rear edge of the base and the adjacent end of said slot adapted to be cut away to permit the sides of the protector to be moved together for purposes of adjusting the protector to sizes smaller than its original size, said slot diverging in width from its front 110 towards its rear end.

In testimony whereof I hereunto affix my signature.

ROY H. ANDERSON.
